UNITED STATES PATENT OFFICE

ELIJAH AVEY, OF POLO, ILLINOIS.

IMPROVEMENT IN DOOR-PLATES.

Specification forming part of Letters Patent No. **158,230**, dated December 29, 1874; application filed November 21, 1874.

To all whom it may concern:

Be it known that I, ELIJAH AVEY, of Polo, in the county of Ogle and State of Illinois, have invented a new and valuable Improvement in Mail Door-Plates; and I do hereby declare that the following is a full, clear, and exact description of the construction and operation of the same, reference being had to the annexed drawings, making a part of this specification, and to the letters and figures of reference marked thereon.

Figure 1 of the drawing is a representation of a front view of my mail door-plate. Fig. 2 is a vertical longitudinal sectional view of the same; and Fig. 3 is a detail view.

This invention has relation to means for facilitating mail delivery by carriers; and it consists in the construction and novel arrangement in connection with a letter-box located on the inside of a door, and having a chute through the same, of a slotted face-plate on the exterior surface of the door surrounding the mouth of the letter-chutes, and a gravitating or vertically sliding door-plate made of sufficiently light material to be readily held up by means of the letter or paper while the same is passing through the chute, whereby the carrier is enabled to compare the letter address with the name on the plate, and to hold the plate up while depositing the letter, with the letter itself, thus using but one hand in the delivery, all as hereinafter fully shown and described.

In the accompanying drawings, the letter A designates the letter-box secured to the inside of the door or partition B, through which is formed the horizontal slot or letter-chute C', above which extends a vertical recess, a.

To the exterior surface of the door is secured a face-plate, b, which is slotted horizontally at C to form the mouth of the letter-chute, around and above which it is located. Through this face-plate, which is at the same time a friction or wear plate, is also formed a vertical slot, c, in which slides the lug of the door-plate.

D represents the door-plate, the front or exposed face of which is suitably inscribed

with the name of the owner of the letter-box, and the back of which is provided with a slide-lug, d, which has a small threaded extension, e, on its rear edge.

Before the friction-plate b is secured to the door, the lug d is passed through the vertical slot c, which should be long enough, when the lug is at its lowest end, to let the door-plate close the chute, and its edge coincide with the edge of the friction-plate, and when the lug is at its upper end to expose the chute. The lug d will project through the slot c, and is passed through the washer f, which is designed to slide on the rear of the wear-plate, and is secured by the nut n, which is screwed on the extension e of said lug. In this manner the door-plate may be securely fastened to the face-plate, and at the same time have a very free movement thereon, in the direction of the guide-slot c.

The door-plate is now raised, exposing the lower portion of the face plate, which is secured in proper position to the door by means of countersunk screws. Then the plate drops of its own weight over the chute-opening, and the device is ready for the reception of letters.

It is preferable that the form of the door-plate should be elliptical, because there will be then no lateral obstruction to the passage of a letter when the central portion of its lower edge is raised sufficiently high to uncover the chute.

A letter-carrier usually has his bundle which he is delivering in one hand, and can thereupon only conveniently use the other in delivering any particular letter. With this device he will have no difficulty.

The plate can be raised by the end of the letter until high enough to expose the mouth of the chute, when the letter can be pushed through into the letter-box. During its passage through the mouth of the chute the stiffness of an ordinary letter will be sufficient to keep the plate up, because its direction of pressure is almost coincident with the plane of the mouth of the chute.

What I claim as new, and desire to secure by Letters Patent, is—

The door B, provided with the recess *a* and chute C, in combination with the face-plate *b*, having the horizontal and vertical slots *c* and *c*, and gravitating door-plate D, provided with the slide-lug *d*, washer *f*, and nut *n*, all constructed and arranged as and for the purpose set forth.

In testimony that I claim the above I have hereunto subscribed my name in the presence of two witnesses.

ELIJAH AVEY.
